COMBINATION REFRIGERATOR AND WARMING OVEN

Montgomery Ferar, Huntington Woods, and Charles R. Russell, Southfield, Mich., assignors to Whirlpool Corporation, a corporation of Delaware

Filed Oct. 18, 1963, Ser. No. 77,034

Term of patent 14 years

(Cl. D67—3)

FIG. 3FIG. 4*FIG. 5*FIG. 5

The dominant features of our design are shown in full lines.

We claim:

The ornamental design for a combination refrigerator and warming oven, substantially as shown and described.
